US00D962873S

(12) **United States Design Patent** (10) Patent No.: **US D962,873 S**
(45) Date of Patent: **** Sep. 6, 2022**

(54) **CONNECTING TERMINAL**

(71) Applicant: **CENTRAL GLASS COMPANY, LIMITED**, Ube (JP)

(72) Inventors: **Kohei Seki**, Matsusaka (JP); **Jun Hamada**, Matsusaka (JP)

(73) Assignee: **CENTRAL GLASS COMPANY, LIMITED**, Ube (JP)

(**) Term: **15 Years**

(21) Appl. No.: **29/796,094**

(22) Filed: **Jun. 22, 2021**

Related U.S. Application Data

(62) Division of application No. 29/692,697, filed on May 28, 2019, now Pat. No. Des. 928,721, which is a division of application No. 29/641,463, filed on Mar. 22, 2018, now Pat. No. Des. 883,227.

CLAIM

The ornamental design for a connecting terminal, as shown and described.

DESCRIPTION

FIG. 1 is a bottom plan view of a connecting terminal showing our new design.

FIG. 2 is a front elevational view thereof.

FIG. 3 is a rear elevational view thereof.

FIG. 4 is a top plan view thereof.

FIG. 5 is a right side elevational view, the left side view being a mirror image thereof.

FIG. 6 is a top, front, left side perspective view thereof; and, FIG. 7 is a top, front, left side perspective view of the connecting terminal, shown in a condition for use.

The broken lines in the drawings depict environmental structure and form no part of the claimed design.

1 Claim, 2 Drawing Sheets
